UNITED STATES PATENT OFFICE

DONALD S. BARROWS, OF ROCHESTER, NEW YORK, ASSIGNOR TO THE GOULD COUPLER COMPANY, OF NEW YORK, N. Y., A CORPORATION OF MARYLAND

SIDE FRAME AND JOURNAL BOX

Application filed April 15, 1927. Serial No. 184,012.

This invention relates to side frames with separable journal boxes and, more particularly, to those having jaws at opposite ends thereof receiving and holding journal boxes therein.

The principal object of my invention, generally considered, is the provision of side frames with journal box receiving jaws at opposite ends thereof, an abutment surface 10 on each journal box and a corresponding abutting surface on each jaw being formed for permitting rocking motion therebetween for equalizing purposes.

An object of my invention is the provision 15 of a journal box of the wedgeless type, that is, one in which the bearing or brass therein directly engages the roof of the box, whereby internal equalization is dispensed with and outside or external equalization of the box 20 between it and the associated frame is provided for.

Another object of my invention is the provision of a side frame with jaws at opposite ends thereof receiving associated journal 25 boxes, the roofs or supporting surfaces of said boxes being preferably formed with cavities or pockets receiving preferably heat-treated inserts attached thereto and presenting convex upper surfaces, the corresponding 30 portions of the receiving jaws being formed with cooperating pockets or cavities receiving preferably heat-treated inserts presenting corresponding convex surfaces for engagement with the convex surfaces of 35 the journal box inserts for permitting equalization of the boxes with respect to the frame.

A further object of my invention is the provision of preferably heat-treated inserts positioned between a side frame and associated journal boxes, the upper insert being securely held in the frame as by means of babbitt, molten steel, welding, riveting or the like, the lower inserts being similarly connected to the journal boxes and presenting 40 convex surfaces toward each other for permitting rocking therebetween and consequent equalization of the journal boxes.

A still further object of my invention is the formation of a journal box not requiring 45 an equalizing wedge between the roof

and bearing thereof, provision being made for corresponding equalization between the box and frame outside of the box.

Other objects and advantages of the invention relating to the particular arrangement 55 and construction of the various parts will become apparent as the description proceeds.

Referring to the drawings illustrating my invention, the scope whereof is defined by the appended claims:

Figure 1 is a transverse sectional view 60 through one end of a side frame on the center line of an associated journal box, an associated bearing and journal being shown in elevation.

Figure 2 is a side elevation of one end of a side frame showing an associated journal box and a portion of the frame in section on the line 2-2 of Fig. 1, looking in the direction of the arrows.

Figure 3 is a fragmentary sectional view 65 corresponding to Figure 1 but showing a modification and illustrating the box raised and tilted for permitting removal of the associated bearing.

Figure 4 is a view corresponding to Figure 2 but further illustrating the modification shown in Figure 3.

Figure 5 is a view corresponding to Figure 4 but showing a further modification.

The operation of a journal and a bearing under conditions of maximum efficiency, which involves minimum friction and wear, requires first a unit pressure per square inch of projected area which will maintain the 85 integrity of the oil film. This permissible pressure per square inch is affected by a number of factors, especially the peripheral speed of the bearing.

It is also requisite that the pressure shall 90 be substantially uniform over the entire area and this can only be so when the bearing is absolutely in alignment with the journal. For a loosely connected structure like a car truck, it is necessary to have an equalizing feature 95 to maintain the alignment of bearing and journal regardless of lack of parallelism between the two side frames and regardless of relative occasional movement between the two. The necessity for accurate alignment of 100

bearings in an automobile crank case for instance is probably known to everyone. If one of these bearing seats were bored on an angle, that particular bearing would carry 5 an unequally distributed load and would speedily overheat and wear.

The standard A. R. A. detail to accomplish the necessary equalization is the drop forged wedge crowned on its upper surface to a 10 78" radius and in contact with the supposedly flat cast roof of the journal box. It has been a matter of common observation that wear takes place between the wedge and the roof of the box so that the original theoretical line 15 contact, if it ever existed, speedily becomes of measurable width, thereby reducing the freedom of movement of the wedge. It will be obvious that the only force, causing the wedge to equalize and correct a misalignment, 20 is the unbalanced pressure on the bearing. In other words, the wedge would not function as designed unless the unit bearing pressure were higher at one end of the bearing than at the other.

25 As the destruction of the oil film results without delay from an unduly high pressure, it is essential that any equalizing means should function immediately. The drop forged wedge in contact with the cast roof of 30 the box does not function immediately.

It is the purpose of this invention to provide hardened crowned surfaces in contact which from their design and composition will maintain for the longest possible time a minimum 35 width of line contact so that the equalizing feature will operate speedily and for a long period without deterioration. I, therefore, 40 form a journal box in substantially the usual way but with no provision for an internal wedge, the roof of the box being formed to receive the brass or bearing directly.

Through the insertion of a hardened crowned wearing plate in the exterior roof of the box and of a similar plate within the jaw of the side frame, I cause the journal box and bearing to remain constantly in proper alignment with the journal, as the whole box 45 equalizes or adapts itself to any deviation of the side frame from a true vertical position. As an incidental advantage, there is 50 hence no relative rocking movement between the axle and the box, as is the case with the internal equalizing wedge. Hence, the wear on the dust guard is less.

55 Now considering the drawings in detail, like parts being designated by like reference characters, and first considering the embodiment of my invention illustrated in Figures 1 and 2, there is shown the end portion of a 60 side frame 1 which is what may be described as a jaw type frame and may be of well known construction or correspond with that disclosed in my application for car trucks, Serial Number 162,137, filed January 19, 1927. Although only one jaw 2 is illustrated, it is

obvious that the frame is symmetrical and provided with a jaw at each end thereof adapted to receive an associated journal box 3.

Each jaw 2 comprises an outer or end member 4 and an inner member 5 between which the side walls 6 of the journal box 3 are embraced. The lower portions of the journal box engaging webs or flanges 7 of the members 4 and 5 may be substantially vertical, the upper portions, however, preferably converging or sloping toward each other and, at their upper ends, joining with a substantially horizontal web or flange 8 adapted to abut or be supported by the associated journal box 3. Said web or flange 8 is formed 75 to present a lower surface 9 to the corresponding portion of the journal box 3, said surface 9 being formed convex or of such a character that it normally engages the mid portion only of the corresponding upper 80 surface on the journal box, whereby rocking motion therebetween for equalizing purposes is permitted. In the present embodiment, the surface 9 is convex but, if desired, it may be flat or concave provided the curvature of such 85 portion is less than that of the associated surface on the journal box. In the preferred embodiment illustrated, however, both surfaces are convex as being the simplest manner for permitting equalization of the box. 90

95 In the embodiment under consideration, the surface 9 is formed on a separate insert 10, the purpose of such being that it may be made of heat-treated or specially hardened steel, thereby improving the wearing qualities thereof and permitting a more efficient 100 equalization. The insert 10 may be retained in place in a corresponding, but larger, cavity 11 in the frame in any desired manner as by forming the cavity 105 with longitudinal lips or ribs 12 and the insert with corresponding lips or ribs 13 and, after insertion in place, filling the space between the insert and the frame with babbitt, molten steel or otherwise securely 110 connecting the parts. Those portions of babbitt 14 or the like, extending longitudinally of the frame on either side of the insert 10, are preferably joined at the ends thereof by laterally extending portions 15, whereby the 115 inserts are securely locked in place and adequate bearing area is provided between the inserts on each side of the longitudinal center line of the frame, said inserts being designed so that the main bearing between the same 120 and the frame will be at the center.

125 The surface 16, on the top of the box 3, formed for rocking engagement with the surface 9 on the frame 2, may, for the same reason, be desirably formed on a hardened or heat-treated insert 17 in the roof or top wall 18 of the journal box 3, said insert 17 being desirably formed interchangeable with the insert 10 and, therefore, tapered longitudinally 130 of the frame as in connection with the

insert 10, the surface 16 thereof being desirably crowned or formed convex transversely of the frame as the insert 10. Likewise, the insert 17 may be held in place in the roof 18 of the box in a manner similar to the securing of the insert 10 to the frame 2. Although the inserts 10 and 17 are crowned transversely of the frame for permitting corresponding equalization thereof, there is no necessity for forming the rocking surfaces of said inserts other than straight longitudinally of the frame as no equalization in that direction is necessary. The surfaces 9 and 16 are, therefore, cylindrical or curved in a transverse direction only rather than spherical or curved in both directions, are preferably convex toward each other, and have corresponding radii of curvature.

The aforescribed construction, permitting transverse rocking or equalization of the box with respect to the frame, obviates the necessity of the usual wedge between the bearing or brass 19 and the roof 18 of the box. This makes it possible to machine the lower surface 20 of the roof 18 of the box, whereby an accurate engagement between said surface and the bearing or brass 19 may be provided. There is no trouble experienced in moving such a brass 19 from between the box 3 and the associated journal 21, it being merely necessary to raise the box slightly and tilt it, as most clearly shown in Figure 3, when the brass may be removed as will be obvious.

In order to permit the desired amount of rocking or equalization between the frame 1 and the journal box 3, the flanges 22 on the box, between which the depending elements 4 and 5 of the jaw are received, preferably flare or diverge downwardly instead of being parallel, as most clearly shown in Figure 1. As in accordance with well known practice, the box is desirably provided with cavities or pockets 23 adapted to receive locking means 24 extending from the outer or end element 4 of the jaw 2 for locking the box with respect to the frame. The object in having two pockets 23 in each box is to avoid rights and lefts in boxes, any box being adapted for connection at either end of the frame. Although I have shown a special or wedgeless box, yet the jaw of the frame is of standard shape so that a box of standard type, not having a hardened insert and containing the usual wedge, can be used interchangeably with the special box illustrated.

Referring now to the embodiment of my invention illustrated in Figures 3 and 4, a construction is there disclosed involving a frame 1^a with a jaw 2^a and a box 3^a, the means for equalization between the box and frame involving inserts 10^a and 17^a providing, respectively, corresponding convex surfaces 9^a and 16^a for permitting lateral equalization of the box, said inserts, however, being of slightly different character in that they

are dove-tailed at their ends as indicated at 25 and 26, respectively, and closely fit the frame at the sides thereof as indicated at 27 and 28, respectively. The cavities receiving the inserts 10^a and 17^a are likewise dove-tailed at their ends as indicated at 29 and 30 and said inserts are locked in position by babbitt or the like 31 filling the space between the ends of the inserts and the corresponding ends of the receiving cavities. Except as specifically described in connection with the present embodiment, the construction thereof may correspond substantially with that of the first embodiment.

Referring now to the embodiment of my invention illustrated in Figure 5, a construction is there disclosed similar to that of the previous embodiments, a frame 1^b of the jaw type being shown with an associated journal box 3^b, the roof of the journal box and the corresponding portion of the frame being provided with inserts 10^b and 17^b, respectively, said inserts, however, preferably corresponding in size with the receiving cavities in the members and being retained in place by rivets 32 and 33, respectively, the adjacent heads of said rivets being preferably countersunk, as indicated at 34 to avoid extension of the same beyond the engaging rocking surfaces 9^b and 16^b. The lower heads of the rivets 33 in the box are preferably inset in the roof 18^b thereof to avoid interfering with the brass 19^b and the upper wall or web 35 of the frame is preferably apertured as indicated at 36 to facilitate driving of the rivets 32 which secure the insert 10^b to the frame. Except as specifically described in connection with the present embodiment, the construction thereof may correspond substantially with that of the first embodiment.

Although special means for providing engaging surfaces on the frame and box for permitting rocking or equalization of the box with respect to the frame have been disclosed, it is obvious that I do not wish to be limited to such, as such surfaces may be provided in other ways and in other places, the invention broadly comprising the provision for equalizing the journal box by means outside of the box as distinguished from the usual wedge. Upon raising the box with respect to the journal and tilting the same with respect to the frame as illustrated, the rear flange 37 of the brass will readily disengage from behind the shoulder 38 on the box, a corresponding disengagement being simultaneously effected with respect to the brass lugs 39.

In view of the foregoing disclosure of my invention, it will be apparent that I have devised means for outside equalization of journal boxes with respect to associated frames involving the substitution of preferably heat-treated or hardened inserts in the boxes and

frames for the usual wedges, such a construction effecting an economy inasmuch as the inserts are smaller and adapted to be more readily manufactured than the wedges. Another advantage effected is that, by outside equalization of the box with respect to the frame, normal tilting of the journal with respect to the box in service, is minimized or practically eliminated, whereby a decrease in movement of the dust guard (not shown) in the dust guard well 40 is permitted with a consequent reduction in the wear on the dust guard.

Having now described my invention, I claim:

1. In combination, a side frame having a jaw at each end thereof, journal boxes embraced by said jaws, upstanding flanges on said journal boxes embracing said jaw portions to limit transverse motion therebetween, and means presenting convex surfaces toward one another for permitting rocking of said boxes with respect to said jaws for equalizing purposes.

2. In combination, a side frame having a jaw at each end thereof, journal boxes embraced in said jaws, the roofs of said journal boxes presenting convex upper surfaces to correspondingly shaped engaging surfaces of the jaws for permitting equalization of said boxes therein, and formed with upstanding flanges lying on either side of said jaw portions for maintaining said boxes in position.

3. In combination, a side frame having a downwardly opening jaw at each end thereof, journal boxes received therein and formed with roofs presenting convex surfaces toward the receiving jaws and formed with flanges extending along said roofs on either side of said jaw portions to limit lateral motion therebetween, said flanges being extended down the sides of said boxes and diverging from one another, the corresponding portions of said jaws presenting convex surfaces to said journal boxes, whereby rocking therebetween with consequent equalization of said boxes is permitted.

4. In combination, a side frame having depending portions forming a jaw at each end thereof, journal boxes embraced by said jaws, bearings in said journal boxes directly engaging the inner surfaces of the roofs thereof, journals engaging said bearings, and locking means extending from said depending portions into corresponding pockets in the boxes for holding them in place.

5. In combination, a side frame having a jaw at each end thereof, journal boxes containing bearings directly engaging the roofs thereof embraced by said jaws, and hardened inserts convex on both sides positioned between the roofs of said journal boxes and the corresponding surfaces of the frame and received in correspondingly shaped pockets

therein for permitting equalizing motion therebetween.

6. In combination, a side frame having a jaw at each end thereof, journal boxes embraced by said jaws, upwardly opening cavities provided in said journal boxes, corresponding downwardly opening cavities provided in said jaws, and interchangeable inserts, respectively, interlocked in said cavities and presenting convex surfaces in engagement with each other for permitting rocking movement between said boxes and frame for equalizing purposes.

7. In combination, a side frame having a jaw at each end thereof, journal boxes embraced by said jaws, bearings in said journal boxes directly engaging the inner surfaces of the roofs thereof and adapted to engage associated journals, said boxes being provided with upwardly opening cavities therein, corresponding downwardly opening cavities in said jaws, and interchangeable hardened steel inserts, respectively, contained in said cavities and presenting convex surfaces in engagement with each other to allow rocking movement between said boxes and frame for equalizing purposes.

8. In combination, a side frame formed with means at either end for receiving a journal box, a journal box connected thereto, each of said journal boxes being formed with a roof, the under surface of which is flat and adapted to directly engage an associated bearing, the upper surface of said roof being formed with an upwardly opening pocket, a hardened insert positioned in said pocket and securely connected to the box, the upper surface of said insert being crowned transversely with respect to the associated frame, that portion of the frame, directly above the insert, being formed with a correspondingly formed pocket in which is connected a corresponding insert, the lower surface of which engages the upper surface of the box insert, whereby transverse equalizing motion between said box and frame is permitted.

9. In combination, a side frame formed with a jaw, a journal box received in said jaw, said box containing a bearing directly engaging and interlocked with the under surface of the roof of said box, the upper surface of said roof and the adjacent surface of the frame being provided with means positioned therebetween interlocked with the corresponding surfaces and having the spaces therebetween filled with metal cast in place, for permitting equalizing motion of the box.

10. In combination, a side frame having a jaw at an end thereof, a journal box received therein, said box being provided with a bearing directly engaging the inner surface of the roof thereof and means comprising interchangeable hardened steel inserts respectively interlocked to the jaw and box for

permitting rocking of the box with respect to the jaw for equalizing purposes.

11. In combination, a side frame having a jaw at each end thereof, journal boxes embraced by said jaws, said boxes being provided with upwardly opening cavities therein, corresponding downwardly opening cavities in said jaws, and interchangeable hardened steel inserts, respectively, contained in said cavities and presenting convex surfaces in engagement with each other to allow rocking movement between said boxes and frame for equalizing purposes.

12. In combination, a side frame having a downwardly opening jaw at one end thereof, a journal box received therein, said journal box being formed with a roof the upper surface of which is formed with an upwardly opening pocket and flanges extending therealong on either side of said jaw portions to limit lateral motion therebetween, said flanges extending down the sides of said box and diverging from one another to permit angling of said box, a hardened steel insert positioned in said pocket and interlocked with respect to the box, the upper surface of said insert being convexly curved transversely with respect to the associated frame, that portion of the frame within the jaw directly above the insert being formed with a corresponding pocket in which an insert interchangeable with the insert in the box is received and interlocked, the lower surface of said insert being correspondingly convexly curved and engaging the upper surface of the box insert, whereby transverse equalizing motion between said box and frame is permitted.

In testimony whereof I affix my signature.

DONALD S. BARROWS.
